UNITED STATES PATENT OFFICE

120,696

DESIGN FOR A SWEATER OR SIMILAR ARTICLE OF WEARING APPAREL

Lorna Whittingham, West Redding, Conn.

Application April 6, 1940, Serial No. 91,507

Term of patent 3½ years

To all whom it may concern:

Be it known that I, Lorna Whittingham, a citizen of the United States, residing at West Redding, in the county of Fairfield and State of Connecticut, have invented a new, original, and ornamental design for a Sweater or Similar Article of Wearing Apparel, of which the following is a specification, reference being had to the accompanying drawing, forming part thereof.

In the drawing:

similar article of wearing apparel, showing my new design, both the front and back thereof being identical; and

Figure 2 is a perspective view, partially in outline, of one of the two halves of the article.

I claim:

The ornamental design for a sweater or similar article of wearing apparel, as shown and described.

LORNA WHITTINGHAM.
